UNITED STATES PATENT OFFICE.

GEORGE YURKANIN, OF TRESCKOW, PENNSYLVANIA.

GAME.

Application filed May 10, 1923. Serial No. 638,017.

To all whom it may concern:

Be it known that I, GEORGE YURKANIN, a citizen of the United States of America, residing at Tresckow, in the county of Carbon and State of Pennsylvania, have invented certain new and useful Improvements in Games, of which the following is a specification.

This invention relates to new and useful improvements in games.

An important object of the invention is to provide a game which will afford much amusement to the players as well as tending to develop a quickness and keenness of the eye.

A further object of the invention is to provide a game of the above mentioned character which may be played by any number of persons all striving to be the first to accumulate the required number of credits necessary to win the game.

Other objects and advantages of the invention will be apparent during the course of the following description.

In the accompanying drawing forming a part of this specification and in which like numerals are employed to designate like parts throughout the same,

Fig. 1 is a plan view of a character embodying this invention which consists of a player having a circular formation,

Fig. 2 is a similar view to Fig. 1 showing a substantially rectangularly shaped character having concaved side edges,

Fig. 3 is a similar view of a character substantially rectangular in formation having inwardly cut substantially V-shaped upper and lower edges,

Fig. 4 is a similar view of a character having a diagonally cut upper edge,

Fig. 5 is a similar view of a substantially rectangularly shaped character having an inwardly cut substantially V-shaped upper edge, and

Fig. 6 is a plan view of a character substantially rectangular in formation with an inverted V-shaped projection forming the upper edge of the same.

In the accompanying drawing, wherein for the purpose of illustration is shown a preferred embodiment of this invention, the numeral 5 designates one of the players which consists of a circular disk having inscribed upon its opposite faces and designated by the character A the word "King"

while a second character *a* represents the value of the player which in this instance is 20. Referring to Fig. 2 there is shown a substantially rectangularly shaped player 6 having concaved side edges 7, the faces of this disk being provided with the word "General" inscribed thereon and designated by the character B, there being further provided, as at *b* the numeral 16 which represents the value of this player. Referring to Fig. 3 there is shown a substantially rectangularly shaped player 8 having inwardly cut substantially V-shaped upper and lower edges 9 while the faces are provided with the word "Captain" designated by the character C and the numeral designated by the character *c* which represents the value of this player, the same being 12.

Fig. 4 shows a further form of player having a diagonally cut upper edge 11 and provided upon its opposite faces with the word "Soldier" designated by the character D while the character *d* designates the counting value of this player which in this instance is 6. Fig. 5 represents a substantially rectangularly shaped player 12 having an inwardly cut substantially V-shaped upper edge 13 while the opposite faces are provided with the inscription of the word "Horse" designated by the character E, there being further provided on these faces the numerals referred to by *e* which represent the value of the player, the same in this instance being 4. Fig. 6 shows a still further form of player which is substantially of rectangular shape having an inverted V-shaped projection 14 forming the upper edge of the same, this player being provided with the word "Sword" designated by the character F and further having inscribed thereon the numeral indicated by *f* which represents the value of this player, the same being 2.

It is to be understood that the various players may be made from any suitable material such as wood, cardboard, or the like and if desired may be formed into other configurations than those shown and described herein, it being necessary, however, to have at least six differently formed players as shown. The players as shown by the various figures are divided into six groups with twenty-three players in all, there being provided one king player, two general players, two captain players, six soldier

players, six horse players and six sword players.

In playing the game, the participants take turns in gathering the entire twenty-three players into one hand, and by employing one of several possible methods of elimination, proceed to reduce the players until there is only one left. The value of this remaining player, as referred to by the characters *a*, *b*, *c*, *d*, *e*, and *f*, is recorded to that person's credit on the score sheet. The total amount of credit necessary to win the game should be decided before starting to play, the score 50 being suggested as an appropriate sum. To make the game more difficult, a ruling may be established that an even count of 50 is necessary to constitute a win. With this rule in effect, it will be seen that a person having a score of 48 will necessarily need the count of one sword player to win, or should a person have 46 credits, the count of one horse player or two sword players will bring his total up to 50 for a win.

As a suggestion of a few of the possible ways of eliminating the players in a person's hand, the party having the play may hold his closed hand having the players therein with the back down and toss the said players into the air. As they fall he may endeavor to catch as many or as few as possible until but one is left. As stated above, the value of this player is recorded to his credit. A further way of playing is to toss the players into the air as just described after which the hand is reversed and an attempt is made to snatch a desired player out of the air. With this method, a person will naturally try to obtain the player most desirable for his score with the result that the game will tend to quicken the eye of the participants. Should the person playing fail to catch at least one player his

turn is forfeited and the next person starts to play.

It is to be understood that the form of this invention herewith shown and described is to be taken as the preferred example of the same, and that various changes in the shape, size and arrangement of parts 50 may be resorted to without departing from the spirit of the invention, or the scope of the subjoined claims.

Having thus described the invention, I claim.

1. In a game of the type described, a series of players divided into several groups, the number of groups being less than the total number of players, and the counting value of the players in any one group being 60 different than such value of players of any other group, the entire number of players being tossed into the air and by an eliminating process, while the players are in the air, reduce the number of players to one 65 for the purpose of obtaining the counting value of the remaining player.

2. In a game of the type described, a series of players divided into several groups, the number of groups being less than the 70 total number of players, the counting value of the players in any one group being different than such value of the players of any other group, and the players in the said groups being of increased number as their 75 counting value decreases, the entire number of players being tossed into the air and by an eliminating process, while the players are in the air, reduced in number until but one player remains for the purpose of obtaining the counting value of the remaining player.

In testimony whereof I affix my signature.

GEORGE YURKANIN.
